UNITED STATES PATENT OFFICE.

NELL Q. DONNELLY, OF KANSAS CITY, MISSOURI.

APRON.

Application filed April 3, 1925. Serial No. 20,350.

To all whom it may concern:

Be it known that I, NELL Q. DONNELLY, a citizen of the United States, a resident of Kansas City, in the county of Jackson and 5 State of Missouri, have invented a certain new and useful Apron, of which the following is a specification.

This invention relates to a new form of apron of such a character that a yoke is 10 provided to fit conveniently around the neck of the wearer and over the shoulders, so that the apron will hang securely without any tendency for the bands of the yoke to slip off the shoulders of the wearer.

15 It is an object of the invention to provide an apron, of a particular form, comprising a yoke and front and back panels attached thereto, and so constructed that the wearer will have perfect freedom of movement without any tendency for the bands of the yoke to slip off the shoulders, and so that the apron will nearly completely cover the ordinary clothing of the wearer.

A further object of the invention is to so design such an apron as to greatly economize in material, and while retaining the above advantages, make it possible to cut the yoke, panels, inserts and associated pieces from a rectangular, or similar piece of goods, with only a very small waste of material.

A further object is to so shape the yoke as to permit of attachment of the panels thereof along lines of attachment which will not necessitate waste of material in cutting the goods.

A still further object is to avoid the usual fastening means ordinarily found in aprons, and thereby to have a complete garment, easily slipped over the head of the wearer and requiring no further operation of adjustment than a mere tying together of the back panels at approximately the waist line.

Further objects of the invention will appear as the following description proceeds.

Accordingly, I have designed an apron as shown in the accompanying drawings which form a part of this specification, and in said drawings,—

50 Fig. 1 represents a perspective view of the apron;

Fig. 2 is a side view thereof;
Fig. 3 is a rear view thereof; and
Fig. 4 is a plan view, showing the arrangement of the cut-out.

55

In said drawings there is shown an apron comprising a yoke 34 having an oval or elliptical cut-out portion for the neck and head of the wearer, of a size to slip over the head of the wearer. The bands of the yoke 60 are, in the above preferred embodiment, cut to somewhat stand out from the body of the garment so as to securely hold the yoke to the shoulders of the wearer without any tendency to slip off.

65

A front panel 31 is attached to the front edge of the yoke, preferably along a straight line, for reasons to be described later. This front panel has a general trapezoidal form, with the lower edge thereof approximately 70 twice as wide as the upper edge, and the length of the panel is much greater than its width reaching below the knees of the wearer and thus presenting very roughly a rectangular shape and hanging when in use 75 in a plane as distinguished from a cylindrical form encircling the body of the wearer (these forms are obviously approximated).

A back panel 32 of similar form is also provided, and attached to the back edge of the yoke, preferably along a straight line, and this back panel is preferably split vertically, and provided with means for tying together the two back panels, in any suitable manner.

80

Inserts 33, 33' of rectangular form, join the front and back panels, these inserts being attached to the panels along their edges as shown, and are preferably of a width approximately half that of the upper edge of the panels. Pockets 35, 35' are provided over the inserts by attaching rectangular pieces of the material to the inserts along a horizontal line and to the adjacent edges of the panels and inserts, preferably along the line where they are joined. The inserts preferably extend from the bottom of the garment to a point about midway to the shoulders, the purpose of this arrangement being to allow perfect freedom of movement to

90

95 the arms and shoulders of the wearer. This opening also permits the apron to be worn 100

over large or loose flowing sleeves without in any way mussing or wrinkling them.

There is thus provided an apron which, except for the omission of the inserts above 5 said midway point, completely protects the dress or clothing of the wearer.

This particular form of panels, yoke and inserts I have found to be of great advantage in the cutting of the material as it 10 makes it possible to take a standard piece of material—for example, one of rectangular form—and cut it in such a manner as to have practically no waste of material.

Thus in Fig. 4 of the drawings it will be 15 seen that the rectangular piece of goods designated by 30 may be cut up to provide a front panel 31, back panels 32, 32', inserts 33, 33', yoke 34, and pocket pieces 35, 35'. By adopting the dimensions previously referred to it will be possible to cut the various pieces to utilize practically all of the material and to have the pieces fit together in such a manner as to make a very attractive apron which will fit the person of the 20 wearer along straight lines without tending to wrinkle or to interfere with the bodily movements.

The various pieces may be advantageously fastened together by bias tape, requiring 25 only a single stitching. The yoke is advantageously made in two pieces, with the seam at the shoulder. It is preferable to attach the yoke to the panels along straight lines in front and rear in order to economize in 30 material in the cutting out of the apron, as otherwise a cut-out would have to be made in the panel portions. By the herein-described arrangement of the yoke, panels and inserts, it is possible to reduce the amount 35 of material required by over 50%, compared with other forms of aprons previously made, taking into account the fact that the present structure of arrangement provides for a complete protection of the clothes or 40 dress of the wearer, except under the arms. The latter may, of course, be filled in with an extension of the inserts, or otherwise. It is preferred to leave it open for convenience of bodily movement, and for convenience of tying, and of taking off the garment, or putting it on.

The material may be of any desired kind, as will readily be apparent, and the uses of the apron so made may vary widely. For 45 example, gingham or cotton aprons for ordinary housework may be made in this manner at a very low cost, and aprons for seamstresses may be similarly constructed from muslin material. On the other hand, rubber aprons for chemical or surgical use may be likewise made, with the same opportunity for economy in material, and for complete protection of the person of the wearer. Leather aprons of a similar cut will also

be found advantageous in various kinds of 65 work where a heavy garment is required for the protection of the person, or the clothes of the wearer.

It is a feature of this invention that the yoke provided for the apron will avoid the 70 usual nuisance found in ordinary aprons due to the slipping off of the shoulder bands and the awkwardness in fastening the apron at the back of the neck. In conjunction with the said yoke, the other parts of 75 the apron have been so proportioned with respect to the yoke that a remarkably small yardage of material is required, without sacrificing anything of the attractiveness of the apron, or of comfort to the wearer, 80 or convenience in use. It will therefore be apparent that I have achieved the advantages of this invention in a simple and economical manner.

The apron may, however, be constructed in such a way that the front panel be extended along the lines of the front yoke, to meet the back panels, extended along the lines of the back yoke, at the shoulders, thus 90 eliminating the yoke. This would, however, require a little additional yardage.

It is a further feature of this invention that the easy adjustment thereof permits of fitting the apron to various sizes and types of figures, so that two sizes only are required to fit figures measuring from 36 to 48 in size.

As many apparently widely different embodiments of this invention may be made without departing from the spirit thereof, 100 it is to be understood that I do not intend to limit myself to the specific embodiments thereof, except as indicated in the appended claims.

I claim:

1. An apron having a yoke, front and back panels attached thereto in front and rear, the panels being of substantially oblong form with the upper edge shorter than the bottom edge, inserts of rectangular form joining said panels and extending from the bottom of the apron approximately half way to the shoulders, said inserts having a width approximately half that of the average width of said panels. 105

2. An apron having a yoke, front and back panels attached thereto in front and rear, the panels being of substantially oblong form, inserts of rectangular form joining said panels and extending from the bottom of the apron approximately half way to the shoulders, said inserts having a width approximately half that of the average width of said panels, and a rectangular piece of goods attached over the upper end of one of said inserts between the panels to 110 form a pocket. 120

3. An apron having a yoke, front and

back panels attached thereto in front and rear, the panels being of trapezoidal form with the upper edge approximately half as long as the bottom edge, inserts of rectangular form joining said panels and extending from the bottom of the apron approximately half way to the shoulders, said inserts hav-

ing a width of approximately half that of the upper edge of the said panels.

In testimony that I claim the foregoing, I have hereunto set my hand this 27th day or March, 1925.

NELL Q. DONNELLY.
